UNITED STATES PATENT OFFICE

CHARLES W. MUELLER, OF ST. LOUIS, MISSOURI, ASSIGNOR TO LEWIS INVISIBLE STITCH MACHINE COMPANY, OF ST. LOUIS, MISSOURI, A CORPORATION OF MAINE

PRESSER FOOT FOR SEWING MACHINES

Original application filed October 15, 1927, Serial No. 226,398. Divided and this application filed August 4, 1928. Serial No. 297,482.

This invention relates to new and useful improvements in a presser foot for sewing machines generally, although the invention is particularly adapted for use in connection with blind stitch sewing machines.

This application is a division of the application filed by me Oct. 15, 1927, Serial No. 226,398 for improvements in blind stitch sewing machines and now Patent 1,739,081, Dec. 10, 1929.

The principal object of my invention is to provide means whereby a presser foot which is rigidly attached at its rear end to the sewing machine frame may have its working plane adjusted into parallelism with the working plane of the work support.

With these and other objects in view which will more fully appear, the nature of the invention will be more clearly understood by following the description, the appended claims, and the several views illustrated in the accompanying drawings.

In the accompanying drawings which illustrate one form of my invention:

Fig. 1 is a front elevation showing the application of my invention in a blind stitch sewing machine,

Fig. 2 is a detail side elevation thereof,

Fig. 3 is a detail top plan view of Fig. 1, and

Fig. 4 is an enlarged top plan view of the presser foot.

Like reference numerals designate corresponding parts throughout the several figures of the drawings.

Referring to the accompanying drawings, my invention includes a sewing machine A having a forwardly extending arm 5 which terminates in a stitching head 6. Journalled in this arm is an oscillatory needle shaft 7 which is actuated by the main shaft 8 journaled in the rear horizontal arm 9. The shaft 7 extends forwardly beyond the front end of the arm 5 and fixed thereto is a needle arm 10 to which a needle 11 is attached by a

clamp 12. Cooperating with the needle to form a line of single thread chain stitches is a looper 13 which is fixed to a looper bar 14 pivotally supported as at 15 on the arm 5 and actuated from the main shaft 8 by suitable connections.

A stationary presser foot 16 is disposed directly below the needle 11 and also below the looper 13. This presser foot is detachably connected to the arm 5 through the medium of a fork 17 which is formed on the rear end of the foot and which cooperates with a clamping nut 18. Formed in the presser foot is a slot 19 having its longitudinal axis extending parallel to the needle rock shaft 7 and in a plane at right angles to the path of oscillation of the needle 11. In order to adjust the working position of the plane of the foot, I have provided said foot at opposite sides thereof with upwardly extending posts 20, 20 having their upper ends provided with flanges 21, 21 which extend over bearing lugs 22, 22 formed on the arm 5. Adjusting screws 23, 23 pass through openings in the flanges and are engaged in threaded openings formed in the lugs. By means of these adjusting screws 23, the plane of the presser foot may be readily adjusted. Clamp screws 24, 24 extend through vertical slots in the posts 20, 20 and have threaded engagement with the lugs 22, 22. By releasing both clamping screws 24, the presser foot may be forced downwardly from its rear or attaching end upon the turning of the adjusting screws 23 in a clock-wise direction, to thereby adjust the plane of the foot relative to the horizontal. If it is desired to elevate the foot, the clamping screws 24 and the adjusting screws 23 are turned in an anti-clock-wise direction, the foot swings upwardly about its attaching end by hand pressure exerted under the front end of the foot, and the clamping screws 24 and adjusting screws 23 are then returned or tightened.

A normally horizontal work support 25 is pivotally supported at its front end and is yieldably held in said horizontal position, as shown and described in my co-pending application Serial No. 226,398, filed October 15, 5 1927, referred to above.

This work support 25 is formed at its left hand corner with a reduced extension 26 which projects towards and under the presser foot 16.

10 Inasmuch as the presser foot is rigidly attached at its rear end to the frame, and the work support is pivoted at its front to the main frame and at a point in front of the foot, it will be readily understood that with 15 materials of different thicknesses, the working plane of the work support will vary in angular relation to the plane of the presser foot bottom.

20 By reason of the adjusting screws 23 and clamping screws 24, the working plane of the foot may be adjusted into parallelism with the inclined working plane of the work support.

25 A work presenting mechanism which I have indicated as a whole by the reference numeral B, is disposed below the presser foot 16 and cooperates therewith. This work presenting mechanism includes an oscillatory 30 feed disc 27 and a work clamp 28 which are specifically described and claimed in my co-pending application referred to above.

35 It is of course to be understood that the details of structure and arrangements of parts may be variously changed and modified without departing from the spirit and scope of my invention.

I claim:

1. In a sewing machine, the combination 40 with a frame including a stitching head, of a presser foot rigidly secured at its rear end only to said head, a normally horizontal work support pivoted on the base in front of the foot and yieldably supported in its normal 45 position, and adjustable supporting means located in front of the securing means and connecting the foot and head to fixedly vary the working plane of the foot.

2. In a sewing machine, the combination 50 with a frame including a stitching head, of a presser foot rigidly secured at its rear end only to said head, and adjustable supporting means located in front of the securing means and connecting the foot and head to fixedly 55 vary the working plane of the foot, said supporting means including a post fixed to and extending upwardly from the foot, and an adjusting screw mounted on the upper end of the post for engagement with the head.

60 3. In a sewing machine, the combination 65 with a frame including a stitching head, of a presser foot rigidly secured at its rear end only to said head, and adjustable supporting means located in front of the securing means and connecting the foot and head to fixedly

vary the working plane of the foot, said supporting means including posts rigidly connected with the presser foot and extending upwardly therefrom, the upper ends of the posts being formed with inwardly extending flanges, adjusting screws cooperating with the flanges for engagement with the head, and means cooperating with the posts and with the head for clamping the presser foot in an adjusted position.

70 In testimony whereof I hereunto affix my signature.

CHARLES W. MUELLER.
